UNITED STATES PATENT OFFICE.

FRANK J. IRVING, OF BUFFALO, NEW YORK, ASSIGNOR TO IRVING ENGINEERING
SALES CO., INC., OF BUFFALO, NEW YORK.

OPERATING MECHANISM FOR RADIATOR SHUTTERS.

Application filed January 11, 1924. Serial No. 685,706.

This invention relates to improvements in means for operating the shutters of automobile radiators.

The objects of this invention are to provide means whereby a shutter may be opened manually, preferably from the driver's seat, and closed automatically when the engine stops; also to provide means of this kind which are so constructed that the shutter may be closed manually at any time, if desired; also to provide a device which, when the engine is in operation, acts to hold the shutter open, and which, when the engine stops, releases the shutter to permit the same to close; also to improve shutter controlling means of this kind in other respects hereinafter specified.

In the accompanying drawings:

Fig. 1 is a longitudinal sectional view of a radiator shutter of a vehicle propelled by an internal combustion engine and the means for controlling the opening and closing of the shutter.

Fig. 2 is a similar view of the controlling means showing the position of the parts when the engine is operating and the shutter is open.

Fig. 3 is a fragmentary sectional elevation thereof on line 3—3, Fig. 2.

Fig. 4 is a similar view showing the positions of the parts when the device is set to be closed.

Figs. 5 and 6 are longitudinal sectional views of two different modified constructions, the construction shown in Fig. 5 being operated by the suction from the engine intake manifold, and the construction shown in Fig. 6 being operated by pressure of the engine exhaust.

On the left in Fig. 1 is shown a shutter of the kind adapted to be placed in front of a radiator (not shown) for cooling the liquid used for cooling the cylinders of an internal combustion engine, and this shutter may be of any suitable or desired kind, and of itself does not constitute a part of this invention. The shutter shown includes a frame or housing A on which are mounted a plurality of plates a which are adapted to swing from the closed position, shown in Fig. 1, to an open position in which the plates extend forwardly to permit air to pass between adjacent plates to the radiator. The plates shown are each secured to rods a', the ends

of which are pivotally mounted in the frame A of the shutter and each rod a' is provided with a crank arm a² by means of which the plates may be swung into various positions. The ends of all of the crank arms are pivotally connected with a connecting rod B in such a manner that a movement of the connecting rod produces a corresponding movement of all of the plates a, and a spring b connected at its opposite ends to the connecting rod and to the frame of the shutter normally holds the connecting rod in a position in which all of the plates are in their closed positions, as shown in Fig. 1. In order to move the connecting rod against the action of the spring b into a position to open the shutter, one of the crank arms a² has an extension or arm b', to which one end of a cord or pull rod c is connected. The other end of this cord extends preferably into proximity to the dash of the vehicle and is secured to a shutter control rod C which is slidably mounted on the dash, instrument board, or other part D of the vehicle. The end of the shutter control rod C is preferably provided with a handle c' of any suitable kind by means of which the shutter control rod may be pulled outwardly, as shown in Fig. 2, to open the shutter.

Any suitable means may be provided for holding the shutter control rod in an outer position so that the shutter will be held open against the action of the spring b during the operation of the vehicle, and in the construction shown, a ratchet mechanism is provided for this purpose, including a pawl or detent E, pivoted at e on a bracket e' secured to the dash or other part D of the vehicle, the pawl engaging with teeth e² which are preferably formed in one face or side of the shutter control rod C. Consequently, when the pawl engages the teeth e², the control rod will be held in an outer position, in which the shutter plates a are held in a position to let air pass through the radiator.

In accordance with my invention, the closing of the shutter is effected by the stopping of the engine and for this purpose, in the construction shown in the drawings, the pawl E is held in position to engage with the teeth e² of the shutter control rod by some means actuated by the engine while in operation, and the pawl is adapted to be moved out of

engagement with the ratchet teeth as soon as the engine stops. This may be accomplished in a number of different ways, three being shown in the accompanying drawings.

5 In the construction shown in Figs. 1 and 2, a magnet coil is employed for holding the pawl in its tooth-engaging position, and the current delivered to the magnet is interrupted as soon as the engine stops. In these figures, F represents a coil of wire which is wound on a spool, forming a solenoid which acts on a plunger or core f extending into the spool, this plunger having a pivotal connection at f' with an arm or extension f² of the pawl E. When the current flows through the coil F, the plunger f will be drawn downwardly into the coil, thus swinging the pawl E upon its pivot e in a direction to cause the pawl to engage the teeth e². The movement 10 of the plunger f into the coil is opposed by any suitable means, such as a spring G, which, in the construction shown, is also arranged within the coil F. Consequently, as soon as the flow of current to the coil F is interrupted, the force pulling the plunger F into the coil ceases to act, thus permitting the spring G to move the plunger upwardly, and so move the pawl E out of engagement 15 with the tooth e², thereby releasing the plunger or control rod C and permitting the spring b to close the shutter.

The current delivered to the coil F may be received from any suitable source, and in the construction shown, this current is taken 20 from the usual ignition switch H of the vehicle, this switch being diagrammatically represented in Figs. 1 and 2. A conductor h from the switch leads to the coil F, and the other end of the coil may be grounded, as indicated at h'. Since the ignition switch is turned off to stop the motor, the turning off of this switch will also interrupt the supply of current to the coil F so that the spring G will consequently move the pawl E out of its holding position, thus permitting the shutter 25 to be closed by the spring b.

Since it may be desirable at times to close the shutter while the engine is in operation, means are preferably provided for disconnecting the pawl E from the teeth e² while the engine is running. This may be done in any suitable manner. In the construction shown for this purpose, the shutter control rod C is preferably substantially circular in cross section and is so mounted on the dash or instrument board D that the shutter control rod may be turned by turning the handle c'. It will be evident that the turning of the rod in this manner will move the teeth 30 out of engagement with the pawl E, as is clearly shown in Figs. 3 and 4. In Fig. 3, the rod C is shown in a position in which the pawl E engages with the teeth thereof, and in Fig. 4, the rod is shown turned so that the teeth are moved out of engagement with the

pawl. When this is done, the shutter control rod is freely movable into the shutter closing position.

In the construction shown in Fig. 5, means are provided for holding the pawl E in engagement with the teeth e² of the shutter control rod by a device operated by the suction produced by the engine while in operation. In this construction, an arm I extending outwardly from the pawl E is connected by means of a pin or link i to a diaphragm K stretched across the open end of a cup k. This cup is connected by means of a pipe k' with the engine intake manifold, or other part which is under suction during the operation of the engine. A spring L arranged within the suction cup k opposes the movement of the diaphragm K by the suction. In the construction shown in Fig. 5, the diaphragm is shown drawn into the cup, due to the suction acting thereon, and the pawl E is consequently in engagement with the teeth e² of the shutter control rod C. When the suction is broken, which occurs when the engine stops, the spring L will move the diaphragm K upwardly, thus causing the pawl E to swing about its pivot and to disengage the teeth e².

In the construction shown in Fig. 6, pressure generated by the engine is utilized for holding the shutter open. In this case, a pawl M is provided to engage with the teeth e², the pawl being pivoted at m on a bracket m' secured to the dash or instrument board D. A cup n, having a diaphragm N stretched across the open face thereof, is connected by means of a tube n' to some part of the exhaust passages of the engine, or other source of pressure, so that when the engine is in operation, pressure will be transmitted to the cup n, thus moving the diaphragm N outwardly. This diaphragm is connected with the pawl M by means of a link or rod o, and a spring O is interposed between the diaphragm N and the bracket m'. Consequently, when the diaphragm N is acted upon by the pressure caused by the operation of the engine, the diaphragm, through the medium of the link o, will move the pawl upwardly into a position to engage the teeth e², this movement being effected against the action of the spring O. When the pressure is interrupted, due to the stopping of the engine, the spring O presses the diaphragm N downwardly and draws the pawl M out of engagement with the teeth e².

It will be obvious that other means operated by the engine may be provided for holding the shutter in the open position during the operation of the engine and for causing the shutter to be closed as soon as the engine stops, the three forms being shown merely for purposes of illustrating some embodiments of my invention.

The shutter control means described have the advantage that they act instantly upon the stopping of the engine, to close the shutter, and thereby conserve as much as possible the heat developed during the operation of the engine, which is particularly desirable in cold weather. The shutter has the advantage over the hand-operated type of shutter in that the memory of the driver is not depended upon to close the shutter. The closing means described are simple and inexpensive in construction and thoroughly reliable in their action, and by providing means for permitting the manual closing of the shutter, the engine need not be stopped in order to adjust the shutter for the desired opening.

I claim as my invention:

1. The combination with a shutter for the radiator of an internal combustion engine, means for normally closing said shutter, a shutter control device for opening said shutter against the action of said closing means, retaining means for holding said device in a shutter opening position, and means actuated by the stopping of the engine to cause said retaining means to release said shutter control device, to cause the shutter to be closed.

2. The combination with a shutter for the radiator of an internal combustion engine, manually controlled means for opening said shutter, a ratchet for holding said shutter open, and means controlled by the engine for releasing said ratchet to close the shutter when the engine stops.

3. The combination with a shutter for the radiator of an internal combustion engine, manually controlled means for opening said shutter, means operating while the engine is in operation to hold said manually controlled means in position to hold said shutter open, whereby the shutter will be closed when the engine stops, and means operable at will for releasing said manually controlled means from said holding means.

4. The combination with a shutter for the radiator of an internal combustion engine, yielding means which tend to close said shutter, a ratchet mechanism for holding said shutter open, means controlled by the engine while running to hold said ratchet mechanism in operative relation to keep said shutter closed, and means operable at will to render said ratchet mechanism inoperative while the engine is running.

5. The combination with a shutter for the radiator of an internal combustion engine, yielding means which tend to close said shutter, a shutter control rod adapted to be moved lengthwise to open said shutter against the action of said yielding means, said rod having ratchet teeth, and a pawl held in engagement with said teeth by the engine while running, said ratchet teeth and

pawl being movable out of engagement at will while the engine is running.

6. The combination with a shutter for the radiator of an internal combustion engine, yielding means which tend to close said shutter, a shutter control rod adapted to be moved lengthwise to open said shutter against the action of said yielding means, said rod having ratchet teeth, and a pawl held in engagement with said teeth by the engine while running to hold said shutter open, said rod being adapted to be turned to move said teeth out of engagement with said pawl, whereby the shutter may be closed manually while the engine is running.

7. The combination with a shutter for the radiator of an internal combustion engine, manually controlled means for opening said shutter, electrically operated means for holding said shutter open, and means for interrupting the flow of current to said electrically operated means when the engine is stopped.

8. The combination with a shutter for the radiator of an internal combustion engine, yielding means which tend to close said shutter, means for opening said shutter against the action of said yielding means, an electro-magnetic device engaging said shutter opening means to hold the same in their opening position, and means for releasing said electro-magnetic device from engagement with said opening means when the supply of current to said electro-magnetic device is interrupted.

9. The combination with a shutter for the radiator of an internal combustion engine, yielding means which tend to close said shutter, a shutter control rod adapted to be moved lengthwise to open said shutter against the action of said yielding means, said rod having ratchet teeth, a pawl adapted to engage said teeth to hold said shutter open, and electro-magnetic means operable while the engine is running to hold said pawl in engagement with said teeth.

10. The combination with a shutter for the radiator of an internal combustion engine, yielding means which tend to close said shutter, a ratchet device for holding said shutter open against the action of said yielding means, and electro-magnetic means which operate while the engine is running to hold said ratchet device in operative relation and which releases said ratchet device to permit the shutter to close when the supply of current to said device is interrupted by the stopping of the engine.

11. The combination with a shutter for the radiator of an internal combustion engine, yielding means which tend to close said shutter, a ratchet device for holding said shutter open against the action of said yielding means and including a pawl, an electro-magnetic device for holding said

pawl in position to keep said shutter open, and means for supplying current to said electro-magnetic device while the engine is running.

12. The combination with a shutter for the radiator of an internal combustion engine, manually controlled means for opening said shutter, an electro-magnetic device

for holding said shutter open, and means connected with the ignition switch of the **10** engine to supply current to said electro-magnetic device when said ignition switch is closed, whereby the opening of said ignition switch will cause the shutter to be closed.

FRANK J. IRVING.
